SUSPENSION CLAMP

Robert L. McCoy, Baltimore, Md., assignor to
General Electric Company, a corporation of
New York

Application August 22, 1947, Serial No. 770,071

5 Claims. (Cl. 248-63)

1

This invention relates to a suspension clamp and more particularly to a suspension clamp for supporting a high voltage transmission line conductor or cable.

It has heretofore been proposed to support a transmission line conductor (the term "conductor" being understood as also describing what might be referred to as a cable) by means of a rigid saddle or envelope type clamp which holds up the conductor and which is, in turn, attached to a support member at the end of an insulator string. Such devices are in common use and perform the function of not only supporting the conductor but also of clamping it against sliding movement.

While such devices are found to be satisfactory for supporting conductors used under what might be termed normal transmission line voltages, it is found that they are decidedly not satisfactory when applied to large diameter conductors used in very high voltage installations to avoid excessive corona loss. Such a conductor would ordinarily be of the hollow core type (or A. C. S. R. type) since external diameter is the important factor rather than solid cross section. A large diameter conductor when used in a transmission line installation is subject to certain physical limitations with respect to its suspension from the ordinary suspension insulator on a supporting tower. Among other things it cannot be supported at a single point or even at a fairly restricted longitudinally disposed area of support, when used in the ordinary long spans involved, since anything in the nature of a sharp bend in the conductor cannot be tolerated. In other words, the supporting clamp must readily accommodate the take-off angles encountered in transmission line construction and at the same time not bend the conductor around too sharp a radius.

Even if made unusually long in the longitudinal direction of the conductor, and even if made with a long sweeping radius of curvature designed to support the conductor in such a manner as to eliminate anything in the nature of a sharp bend at the effective center of support, the conventional rigid saddle or envelope type clamp is still not completely satisfactory for supporting large diameter conductors or cables of the type mentioned above. For one thing, such a conventional clamp would have to be unduly bulky or large in order to have sufficient strength. Furthermore, even if the radius of curvature of such a clamp were made long and sweeping in order to accommodate a large diameter conductor, it is found in practice that the profile of a conductor at any particular tower support cannot be definitely determined in advance and, accordingly, there is no assurance that the predetermined curvature of a conventional type clamp would be correct for the particular tower installation involved. Since

2

a conventional type clamp would be necessarily large in order to have sufficient strength to support a large diameter conductor of the type under discussion, it follows that such a clamp would have considerable inertia, thereby preventing it from effectively following movements of the conductor caused by windage or other conductor vibrations. As a result, there is a tendency for the conductor to pound or beat against the clamp where the conductor becomes tangent to, i. e. makes initial contact with, the clamp which results in work hardening of the conductor material and greater susceptibility to material fatigue at this location. This, of course, can result in conductor fracture.

Having the foregoing in mind, I have found that the disadvantages of a conventional rigid saddle or envelope type clamp can be overcome by providing a suspension clamp having a number of rugged lightweight parts flexibly disposed with relation to each other. In my invention, the conductor is supported on an odd number of separate saddles preferably three. Each of these saddles is provided with supporting trunnions and these trunnions are connected by flexible linkages, thereby providing a flexible link interconnection between each individual saddle. The interconnecting linkages and, of course, the individual saddles, are supported from the lower fitting of an insulator string by other links attached to the interconnecting linkages at some desired point between the trunnions of the individual saddles.

By this type of construction the total weight of the suspension clamp is considerably reduced inasmuch as a number of relatively small individual parts are substituted for a large mass, said mass being necessarily large both because of strength requirements and because it has to be made so in order to get a sweeping radius of curvature. The total weight of the span to be supported is divided among individual supporting saddles and the weight proportion borne by each saddle is capable of adjustment by suitably proportioning the lengths of the links interconnecting the individual saddles. Besides conforming to the conductor profile at a particular supporting tower, the clamp also tends to be self-adjusting to span conditions which might arise in service. There is little possibility of the conductor leaving contact with any one of the saddles under vibratory conditions since each saddle is made relatively short, individual saddles can move vertically relative to each other, and the whole clamp can pivot about the main supporting lug carried by the insulator. Pounding or beating of the conductor against the saddle seats and flexing of the conductor are thereby effectively minimized. It will thus be seen that the disadvantages found with the conventional rigid saddle or envelope type clamp are effectively overcome.

Accordingly, it is an object of my invention to

provide a new and improved suspension clamp having a number of rugged lightweight parts flexibly disposed with relation to each other.

It is another object of my invention to provide a means for supporting a transmission line conductor or the like on a number of supporting members and relating the supporting effort of said supporting members in such manner that a change in the supporting effort of one of said members results in a movement of said supporting means and an opposite change in the supporting effort of another of said members which tends to return the supporting effort of the first mentioned member to its original value.

It is a further object of my invention to provide a new and improved suspension clamp for supporting a transmission line conductor or the like having a plurality of conductor supporting saddles interconnected by a system of linkages and adapted to yieldably support a relatively large diameter conductor in such a way as to conform to the natural profile of the conductor.

It is still another object of my invention to provide such a clamp which, while itself is effectively supported from a single point, supports the conductor at a plurality of points to give a predetermined weight distribution as between the plurality of supporting points.

It is a still further object of my invention to provide such a clamp in which the tendency of the conductor to leave the clamp and subsequently beat thereagainst is minimized by permitting relative vertical movement of the individual conductor supporting saddles and also permitting rotation of the entire clamp assembly about a central supporting member in the event that conductor vibrations occur.

It is still another object of my invention to provide such a clamp in which friction caused by relative movements between the clamp parts tends to impose a damping action in the event of conductor vibrations.

These and other objects and advantages of my invention will become apparent from the following detailed description taken in conjunction with the attached drawing in which Figure 1 is a side elevation of my conductor suspension clamp; Figure 2 is a top or plan view; Figure 3 is a cross-sectional view taken on line 3-3 of Figure 1; Figure 4 is a cross-sectional view taken on line 4-4 of Figure 1; and Figure 5 is a cross-sectional view taken on line 5-5 of Figure 1.

In the embodiment of my invention illustrated on the drawing, and referring more particularly to Figures 1 and 2, it will be observed that a hollow core type conductor 10 is supported on three spaced saddle members designated generally at 11, 12, and 13. These supporting saddle members are, in turn, pivotally supported by angular shaped link members designated generally at 14 and 14', and 15 and 15'. As will be explained more in detail hereinafter, adjacent ends of the angular shaped links 14 and 15, and 14' and 15' overlap and are pivotally connected to the center saddle supporting member 12. Furthermore, it can be observed that the links 14 and 14' are of identical shape and are spaced apart on either side of the hollow core conductor 10; the same is true of the links 15 and 15'.

The angular shaped links just described are, in turn, supported by curved links 16 and 16', and 17 and 17' which may be referred to collectively as a support yoke. Adjacent ends of these curved links, such as those of links 16 and 17, overlap and are pivotally connected, in a man-

ner explained more in detail hereinafter, to a vertically depending supporting lug 18 which is secured to a member such as the bottom insulator 19 of a string of insulators. Since the curved link 16' is positioned in spaced relation to the curved link 16 on the other side of the hollow core conductor 10 and the curved link 17' is similarly positioned with respect to curved link 17, adjacent ends of the curved links 16' and 17' also overlap and are pivotally connected to the main supporting lug 18. Actual supporting of the angular shaped links 14, 14', 15 and 15' by the curved links 16, 16', 17 and 17' is achieved through a pivotal type connection between the outer ends of the curved links and an intermediate portion of the angular shaped links in a manner which will be described more in detail hereinafter. It is sufficient merely to note at this point that the curved links support the angular shaped links through the medium of pivotal connections, and that the angular shaped links likewise support the saddle members through the medium of pivotal connections, thereby producing an extremely flexible type support for the conductor 10, and one that is pivotal as a whole about the main supporting lug 18.

Since the supporting saddles 11, 12 and 13 actually engage the conductor 10, these saddles can be referred to as primary supporting members. Furthermore, since the angular shaped links 14, 14', 15 and 15' support the saddle members, the angular shaped links can be described as being secondary supporting members. Finally, since the curved links 16, 16', 17 and 17' support the angular shaped links, the curved links can be referred to or described as being tertiary supporting members. This language is a convenient way of describing the various supporting members insofar as their actual engagement with the conductor 10 is concerned.

Considering the individual supporting saddles, the saddle members 11 and 13, which might be termed the outer saddle members since they are positioned an equal distance on either side of the central saddle member 12, are constructed alike and for this reason it is deemed unnecessary to describe both in detail. Instead, only the outer saddle member 13 is so described.

This saddle member is shown in Figures 1 and 2 and is also shown in cross-section in Figure 5. From these figures it can be seen that the saddle member 13 includes a saddle seat portion 20 having a liner 21 thereon which bears against the underside of conductor 10 throughout approximately 180° of the circumference of this conductor. The liner 21 is of the same material as the conductor hence assuring metal-to-metal contact between the same, instead of different metals, thereby avoiding electrolytic action and conductor wear if the saddle itself is a metal harder than the conductor. In a typical installation, the conductor 10 and liner 21 are made of copper whereas the saddle proper is made of galvanized mild steel. The sides 22 and 23 of saddle member 13 extend upward and are approximately the height of the conductor 10 when the latter is positioned in the saddle member. Midway of these saddle member sides 22 and 23, trunnion members 24 and 25 are formed thereon and extend at substantially right angles away from the sides, as can be observed from Figure 5. The trunnion members 24 and 25 are substantially circular in cross-section, at least adjacent the saddle sides 22 and 23, and the common axis of these trunnion

members passes through the center of the conductor 10. Trunnion 24 is made slightly longer than trunnion 25 in order to obtain proper centering of saddle 13 with respect to center saddle 12. The saddle seat 20, liner 21, and sides 22 and 23 are flared outwardly to provide a conventional bell-mouth shape at each end of the saddle as indicated at 26 and 27. The arrangement, of course, avoids presenting a sharp edge to the conductor as it rests on the saddle.

Referring now to the angular shaped links 15 and 15', it can be seen that the arms 28 and 29 of these links each contains, adjacent the end of the arm, a generally circular opening. For example, the arm 28 contains the opening 30 and the arm 29 contains the opening 31. These openings are for the purpose of receiving the ends of trunnion members 24 and 25 in order that these trunnion members and, in turn, the saddle member 13 can be supported by the links 15 and 15'. Referring particularly to Figure 5, it is observed that the end 32 of trunnion member 24 is stepped down in diameter from the remainder of the trunnion member and extends through the opening 30 in arm 28 of link 15. Furthermore, this end 32 of the trunnion member 24 is provided with a downwardly extending or overhanging lip 33 which, and particularly when a weight is imposed on saddle member 13, overhangs the lower side of openings 30, thereby providing a catch and preventing slippage of the end 32 of trunnion 24 inwardly through this opening. As an added precaution against such slippage, a safety cotter pin 34 is provided. The arrangement for the oppositely extending trunnion member 25 which extends through opening 31 in arm 29 of link 15' is the same as that just described with regard to trunnion 24 and hence no need is seen to repeat the details of such description. Since the saddle member 13 is thus pivotally supported on a centerline which passes through the center of the conductor 10, the saddle member can readily conform to the take-off angle of the conductor with respect to the whole clamp. As was previously mentioned, the arrangement of parts for saddle 11 is the same as the arrangement for saddle 13 and since this latter arrangement has been described in detail, no need is seen to repeat such details with respect to saddle member 11.

The center supporting saddle 12 is constructed generally similar to the outer supporting saddles 11 and 13 but is larger than either of said supporting saddles. For one thing, the center supporting saddle 12 is longer than either of the outer supporting saddles, this meaning that the center supporting saddle engages the conductor 10 along a greater portion of its length than either of the outer supporting saddles. Like the outer supporting saddles, the center supporting saddle 12 includes a saddle seat portion 35 having a liner 35' thereon which bears against the underside of the conductor 10 throughout substantially 180° of the circumference of this conductor. Such engagement can be observed from Figure 3. Also, like the outer supporting saddles, the center supporting saddle 12 includes saddle side members 36 and 37 but these saddle side members do not have as great a height as do, for example, the saddle side members 22 and 23 of saddle 13 since the center saddle 12 is provided with a clamping member 38, the details of which are described later in this specification. Because of this clamping member 38,

the saddle side members 36 and 37 do not extend quite to the top of the conductor 10 when the latter is positioned in saddle 12.

However, and like the arrangement for the outer saddles 11 and 13, trunnion members 39 and 40 are formed on the center saddle side members 36 and 37 approximately midway of the length of these side members. Furthermore, as can be observed from Figure 3, the common axis of these trunnion members 39 and 40, which are generally circular in cross-section, passes through the center of the conductor 10. Trunnion member 39 is stepped down in diameter adjacent its end 41, as is shown in Figure 3, and this end 41 is provided with a downwardly extending lip 42.

Adjacent ends of arms 43 and 44, these arms being parts of, respectively, angular shaped links 15 and 15', are each provided with a generally circular opening, these openings being designated at 45 and 46, see Figure 3. When my suspension clamp is in assembled condition, the adjacent ends of link arms 43 and 44 overlap, as shown in Figures 1, 2 and 3, so that openings 45 and 46 are in registry with one another and are so positioned as to receive the stepped-down diameter portion of trunnion 39 which is adjacent the end 41 of said trunnion. By this arrangement, the trunnion 39 is supported by link arms 43 and 44, since the trunnion can bear against the lower sides of the openings 45 and 46 in these link arms. When weight is applied to the center saddle 12, this causes the trunnion 39 to exert a force downward on the link arms 43 and 44 and also causes the lip 42 to overhang the lower edges of the openings 45 and 46 more positively, thereby preventing inward movement of trunnion 39 with respect to the link arms 43 and 44. If desired, a safety cotter pin 47 can also be provided. The arrangement for trunnion member 40 and the engagement of this trunnion member with adjacent ends of angular links 15 and 15' is the same as that just described with respect to trunnion 39 and hence it is not deemed necessary to repeat details of the arrangement for supporting trunnion 40.

As was previously mentioned, the angular shaped links 14, 14', 15 and 15' are supported by the curved links 16, 16', 17 and 17'. This support is accomplished at a point adjacent the ends of the curved links, and likewise adjacent the bend in the angular shaped links, and the supporting arrangement involving links 14 and 14' and links 16 and 16' is described in detail, it being understood that the supporting arrangement involving links 15 and 15' and 17 and 17' is identical thereto.

With reference to Figures 1, 2, and 3, the curved links 16 and 16' are rigidly attached to spacer sleeves 48, 49 and 50. While any suitable means of achieving a rigid connection between these links and the spacer sleeves can be used, I have illustrated fillet-weld connections 51 for accomplishing this. By virtue of the connection between the sleeves 48-50 and links 16 and 16', it can be seen that movement of the links can result in movement of the sleeves as a unit. A bolt 52 extends through aligned openings in the links 14, 16, 16' and 14' and is surrounded by the sleeves 48-50. The openings in links 14 and 14' are of less diameter than the outside diameters of spacing sleeves 49 and 50 whereby, when the bolt 52 is tightened against washers 53 which engage the outer sides of links 14 and 14', these links are tightened against the ends of sleeves 49 and 50.

but are not, however, rigidly attached thereto. This allows pivotal movement of the links 16 and 16' with respect to the links 14 and 14'. Also, the pivotal engagement of the links 16 and 16' with bolt 52 obviously causes these links to support the links 14 and 14'. In order to tighten the bolt 52, I use an ordinary hexagonal nut 54 and also provide a safety cotter pin 55.

The overlapping ends of links 16 and 17, and 16' and 17' respectively, are retained in overlapped position by the following arrangement. A bolt 56 extends through opening 57 in the bottom portion 58 of supporting lug 18. This bolt 56 also passes through openings such as the openings 59 and 60 adjacent the ends of curved links 16 and 17. Similar openings are provided adjacent the overlapping ends of links 16' and 17'. The bottom portion 58 of lug 18 acts as a spacer between the overlapped ends of links 16 and 17 and the overlapped ends of links 16' and 17'. Accordingly, when the bolt head and nut 61 are tightened against washers 62, the overlapped ends just mentioned are held in properly spaced relation and are free to pivot with respect to each other. A safety cotter pin 63 is provided.

It is to be further noted that the curved links 16, 16', 17 and 17' are not rigidly attached to supporting lug 18 but, instead are pivotally connected thereto. The avoidance of a rigid connection between the curved supporting links and the supporting lug 18 enables the entire assemblage of links and saddles to rotate as a unit about lug 18. Such action might result if one side of the clamp, considered in a direction lengthwise of the conductor, is subjected to greater rotational stresses than the other side.

Referring more particularly to Figures 2 and 4, it will be seen that the central supporting saddle 12 is provided with a clamp for securing the conductor 10 against longitudinal movement with respect to the saddle. This clamp, considered as a unit, comprises the saddle 12 itself, a keeper block 38, and U-shaped clamping bolts 64 and 65 which are secured in place by means such as the nuts 66 and 67. Taking the U-shaped clamping bolt 65 as an example, this bolt passes through openings in oppositely disposed ears saddle 68 and 69 which are formed integral with saddle member 12. The clamping nuts 67 engage the underside of these ears and pull the clamping bolt 65 firmly against keeper 38, the liner 70 of which, in turn, engages the upper surface of conductor 10 to hold the latter firmly in place against saddle seat liner 35'. The bore of saddle member 12, i. e. the bore of the seat portion 35 and the sides of the saddle member, in association with the keeper block 38 is designed to correspond as nearly as possible with the diameter of the conductor 10 so that when the keeper block is drawn down on the conductor the supporting saddle and keeper block will make a close fit with the conductor throughout approximately 90% of its circumference. Notice that the saddle sides are recessed at 71 and 72 to accommodate the lower edges of the keeper. This arrangement permits the clamp to be drawn tightly around the conductor to restrict the same against longitudinal movement without tending to crush or deform the conductor. The ends 73 and 74 of saddle 12 and the ends 75 and 76 of keeper 38 are flared outward to form the conventional bell-mouth arrangement for preventing damage to the conductor.

While I have shown a clamping arrangement for securing the conductor 10 against longitudi-

dinal movement with respect to the center saddle 12, and have shown the outer saddles 11 and 13 without any corresponding clamping arrangement, it will be understood that if it is desired to do so clamps may likewise be applied to these outer supporting saddles 11 and 13.

From the foregoing description it will be apparent that I have provided a relatively lightweight suspension clamp for supporting large diameter high voltage conductors, such as are used in transmission line installations, and that the clamp is made up of a number of rugged lightweight parts assembled together in what might be termed articulated relation, thereby providing freedom of movement between individual parts. The suspension clamp arrangement, as viewed in side elevation, is symmetrical so that the conductor is supported in a uniform manner, conforming with its profile, with respect to a central point of support. For example, in the particular embodiment illustrated, the conductor 10 is supported at three locations, i. e. the saddle members 11, 12 and 13, spaced apart longitudinally of the conductor. Furthermore, the outer saddles 11 and 13 are symmetrically disposed with respect to the central saddle 12 and the latter is positioned substantially on a center line extending vertically downward from the supporting lug 18 which is attached to the bottom insulator 19. This means that there is a distributed support arrangement whereby a balanced support of the conductor 10 is obtained with respect to the insulator 19.

By suitably proportioning the dimensions of the angular shaped links 14, 14', 15 and 15', the spacing of the points of support and the weight distribution as between the respective conductor supporting saddles can be predetermined at will so as to achieve the correct take-off angle at the outer saddles. With the proportioning illustrated in the drawing, that is, the proportioning of the length of arms such as arms 28 and 43 of link 15, the weight distribution is such that approximately 60% of the total weight of the span is supported at center saddle 12 and approximately 20% is supported at each of the outer saddles 11 and 13. Of course, it will be understood that this relationship or proportioning of the arms such as arms 28 and 43 of link 15 is merely illustrative and that the weight ratio could be changed to conform to other desired distribution ratios as between the center saddle support and the outer saddle supports.

It will be observed that the angular shaped links, such as links 14 and 15, are of bell crank shape with the elbow of the bell crank located below the center line of the conductor 10. Inasmuch as the upper or curved supporting links, such as 16 and 17, are attached to these bell crank links 14 and 15, substantially at the elbows of the latter, the ends of each bell crank shaped link can pivot about the connection at the elbow and hence, for the arrangement shown in the drawing, the individual saddles 11, 12 and 13 can move vertically relative to each other. Since such movement can take place as between respective saddles, a change such as a decrease in the weight load on one saddle is normally accompanied by a change in the opposite direction, i. e. a weight increase on another saddle, and this latter change, through the medium of the bell crank link arrangement returns the first changed saddle back to its original weight carrying status. In this manner the mechanism is self-adjusting and tends to maintain the predeter-

mined weight distribution between relative saddles, previously referred to. Furthermore, it will be noticed that the center supporting saddle 12 is linked to each of the outer supporting saddles 11 and 13, whereby a change in the weight load on either of the outer saddles will cause a change in the weight load on the center supporting saddle, and vice versa. This not only maintains weight distribution but also maintains symmetry.

Because of the lightness of the individual parts of my mechanism these parts, such as the supporting saddles, have low inertia and can readily follow conductor movements such as movements of the conductor away from the outer supporting saddles thereby effectively preventing pounding and beating of the conductor against the saddles. This means that when the self-adjusting action of the suspension clamp takes place there is no appreciable inertia of parts tending to hinder such action. Some damping of conductor vibration is achieved by reason of the natural friction between a number of moving parts. This clamping can be increased by tightening nuts, such as 61 and 54, or by providing spring washers at 53 and 62, or both.

By using the arrangement which I have described, it is possible to reduce the clamp dimensions considerably as compared to a conventional rigid saddle clamp. To illustrate, for a line requiring 1.65" diameter hollow conductor it was found that the rigid saddle type clamp would be 34" long, whereas my type clamp totaled 21½" in length. By placing the curved supporting links, such as 16 and 17, between the angular shaped links, such as 14 and 15, the width of the clamp is kept down. The curvature of links such as 16 and 17 enables them to clear the center saddle assembly. Total height of the clamp is kept down by the curved link arrangement and the connecting of these links to the angular links at elbows located lower than the conductor. The arrangement is thus both relatively light and compact.

In the embodiment of my invention which I have selected for illustration and description, I have shown a three-saddle supporting arrangement. It is not critical to the practice of my invention that three saddles only be used, although such a number of saddles is rather desirable from a practical standpoint. If desired, a greater number of supporting saddles could be utilized but, in view of symmetry requirements and the fact that to achieve such symmetry one saddle is best located beneath the main support member attached to an insulator string, this dictates that an odd number of supporting saddles should be provided. For a number of saddles greater than three, an interconnecting linkage arrangement similar to that which I have illustrated and described can readily be provided.

Accordingly, while I have shown and described a particular embodiment of my invention, I wish it to be understood that I do not intend to be restricted solely thereto but that I do intend to cover all modifications thereof which would be readily apparent to one skilled in the art and which come within the spirit and scope of my invention.

Having thus described my invention, what is claimed as new and desired to be secured by Letters Patent is:

1. A cable supporting device comprising three equally spaced apart aligned supporting saddles positioned along a common axis, trunnion mem-

bers on each of said saddles, there being a trunnion member projecting from each side of a saddle member, a pair of spaced bell crank shaped levers pivotally connecting each adjacent pair of saddle members, said saddle members being positioned between said levers and the trunnion members on said saddle members engaging said levers, adjacent ends of said levers being positioned in overlapping relation at the middle saddle member and being pivotally connected to the trunnion members thereon, a pair of supporting links pivotally connected to each pair of bell crank shaped levers adjacent the elbows thereof, and support means pivotally connecting said supporting links to each other, said last named means being positioned above the middle saddle member.

2. A device for supporting a transmission line conductor, said device comprising an odd number of equally spaced apart support saddles, a plurality of links interconnecting said saddles for relative movement with respect to each other, a central supporting member, and a support yoke pivotally connected to individual links in between said support saddles and pivotally connected to said central supporting member.

3. A suspension clamp comprising a central supporting member, an odd number of supporting members in tandem spaced relation, one of said supporting members being positioned symmetrically with respect to said central supporting member, linking levers pivotally mounted on said supporting members interconnecting said members in adjustable spaced relation in accordance with a selected weight distribution ratio, and links extending from said levers to said central supporting member, said links being pivotally connected to said levers between the pivoted connections to said supporting members and also pivotally connected to said central supporting member.

4. A cable suspension clamp comprising a central supporting member, three supporting saddles in tandem spaced relation, the middle one of said saddles being positioned symmetrically with respect to said central supporting member and the outer saddles being spaced equally from said middle saddle, an angular shaped link connecting each adjacent pair of saddles, the ends of adjacent links being overlapped and pivotally connected to the middle saddle, each link including arms of unequal length, and additional link members pivotally connecting said angular shaped link to said central supporting member.

5. A cable suspension clamp as claimed in claim 4 in which the pivotal connection of the angular links to the additional link members is on the opposite side of the saddles from the connection of the additional link members to the central supporting member.
